ATTORNEY

UNITED STATES PATENT OFFICE.

LEWIS P. WENTZELL, OF GREENSBURG, PENNSYLVANIA.

CHANNEL-IRON AND ANCHOR.

1,395,070.

Specification of Letters Patent.

Patented Oct. 25, 1921.

Application filed May 7, 1920. Serial No. 379,626.

To all whom it may concern:

Be it known that I, LEWIS P. WENTZELL, a citizen of the United States, residing at Greensburg, State of Pennsylvania, have invented new and useful Improvements in Channel-Irons and Anchors, of which the following is a specification.

This invention relates to securing means, and more particularly to means for securing 10 metal lath to the ceilings and walls of rooms and other structures.

One of the main objects of the invention is to provide simple and efficient means for securing metal lath to buildings of steel 15 frame construction. A further object is to provide means by which the lath may be held in proper position and readily secured. Another object is to provide securing means 20 of the character stated which may be produced at small cost and can be readily applied. Further objects will appear from the detailed description.

In the drawings:—

Figure 1 is a transverse section through a 25 securing means constructed in accordance with my invention.

Fig. 2 is a fragmentary side view of the supporting rod and connector.

Fig. 3 is an end view of the same.

Fig. 4 is a transverse section through the 30 supporting rod and the metal lath, the securing clip being open.

Fig. 5 is a side view of the rod and clip.

Fig. 6 is an edge view of a modified form 35 of clip.

Fig. 7 is a side view of the same.

I provide a supporting bar 1 which is pressed out of sheet metal to form a V-shaped body 2 depending from a neck 40 formed by parallel arms 3 which are formed at their upper edges with outwardly directed flanges 4, these arms being connected at their lower edges to the sides of body 2 by downwardly and inwardly inclined shoulders 5. In practice, a suitable number of these bars are secured by flanges 4 to the bottom flanges of the I beams A of the structure in spaced parallel relation.

To secure the lath 6 to the bar, a wire 50 clip 7 is passed through adjacent meshes of the lath so as to straddle a web element 8 thereof. This clip is formed of relatively soft spring wire so that, as it is forced upwardly over the body 2 of the bar, arms 9 are forced apart. Each arm is provided

at its upper end with a hook element 10 adapted to engage snugly over shoulder 5 of the bar. When the clip reaches its uppermost position, elements 10 snap over the shoulders 5, and arms 9 press tightly against the sides of body 2 of the bar thus effectively securing the clip in position. At its lower end the clip is bent to form an eye 11 connected to the body of the clip by a constricted portion or neck 12. After the clip has 60 been attached to the bar eye 11 it is grasped by a pair of pliers or other suitable tool and twisted so as to twist the constricted portion 12 thus securing web element 8 tightly against the bar as illustrated in Fig. 1. By 70 this means the lath may be held in the desired position and quickly and easily secured to the bar in the manner described.

When it is desired to connect two aligned bars I employ a connector 13 such as that 75 illustrated in Figs. 2 and 3. This connector is pressed out of sheet metal and is of a size and shape to fit snugly with the body 2 of the bar, a suitable portion projecting beyond the end of the body for insertion into the 80 end of the adjoining bar. By this means two bars may be readily connected in such manner as to provide a rigid and strong connection.

The form of securing clip illustrated in 85 Figs. 6 and 7 is formed by bending from a strip of sheet metal to provide arms 9^a provided at their upper ends with hook elements 10^a. These arms are connected at their lower ends by a straight and flat gripping and 90 securing element 11^a. After the clip has been inserted through the lath and attached to the bar in the manner previously described, element 11^a is bent over at right angles to the body of the clip thus securing 95 the lath.

As will be understood, and as indicated herein, slight changes may be made in the construction and arrangement of parts of the invention without departing from the 100 field and scope of the same, and I intend to include all such variations, as fall within the scope of the appended claims, in this application in which a preferred form only of my invention is disclosed.

What I claim is:—

1. In a device of the character described, a bar including a body having lateral downwardly converging elements provided at their upper ends with shoulders projecting 110

laterally of the body, and a clip fitting about said body and provided with elements engaging over said shoulders.

2. In a device of the character described, 5 a bar including a substantially V-shaped body provided at its upper end with laterally projecting shoulders, and a substantially V-shaped resilient clip fitting about the sides of said body and provided at the 10 upper ends of its arms with elements engaging over said shoulders.

3. In a device of the character described, 15 a bar including a depending substantially V-shaped body provided at its upper end with laterally projecting shoulders, and a clip of substantially V-shape fitting about the sides of the body and provided at the upper ends of its arms with elements engaging over said shoulders, the arms of said

clip being connected by an enlarged element 20 to facilitate gripping and twisting together of the arms at their lower ends for securing lath through which the clip is inserted.

4. In combination, a bar including a depending substantially V-shaped body provided at its upper edge with laterally projecting shoulders, metal lath positioned adjacent to the lower edge of said body, and a clip inserted through adjacent meshes of the lath and fitting about said body, said 30 clip being provided at the upper ends of its arms with elements engaging over said shoulders, the lower end of the clip being bent against the lath so as to hold the same pressed against the lower edge of the body. 35

In testimony whereof I affix my signature.

LEWIS P. WENTZELL.
